UNITED STATES PATENT OFFICE.

HARLEY C. MOULTON, OF MAPLEWOOD, MISSOURI, ASSIGNOR TO LEWIS INVISIBLE STITCH MACHINE COMPANY, OF ST. LOUIS, MISSOURI, A CORPORATION OF MAINE.

BLINDSTITCH-SEWING MACHINE.

Application filed July 10, 1924. Serial No. 725,136.

To all whom it may concern:

Be it known that I, HARLEY C. MOULTON, a citizen of the United States, and a resident of Maplewood, county of St. Louis, State of Missouri, have invented an Improvement in 5 Blindstitch-Sewing Machines, of which the following description, in connection with the accompanying drawing, is a specification, like characters on the drawing representing like parts.

This invention relates to improvements in blind stitch sewing machines for sewing the edge portion of a superimposed layer upon a base layer of material by a series of blind 10 stitches in both the base and superimposed layers and the general object thereof is to provide means for insuring accuracy and uniformity of the stitches in the superimposed layer.

20 A further object of the invention is to provide a mechanism which will enable uniformity of stitching in a superimposed layer of very fine or sheer material.

A further object of the invention is to 25 provide adjustable means for guiding the edge of the superimposed layer which will enable the production of uniform and accurate stitches in the superimposed layer and also enable such adjustment to be made as 30 may be necessary or desirable to accommodate goods of different thicknesses, quality or character.

More particularly the invention relates to 35 improvements in blind stitch sewing machines for felling a superimposed layer of material upon a base layer comprising a needle reciprocable in the general direction of the line of feed with guiding means, preferably carried by the presser foot, for directing 40 the upturned edge portion of the superimposed layer into the path of the needle, with a gauge also preferably carried by the presser foot located in proximity to the needle path and preferably embracing the edge 45 of the superimposed layer at the stitching point and yieldable to the passage of the needle and the material of the superimposed layer which is caught by the needle upon its penetrating stroke.

50 A further object of the invention is to provide an improved presser foot for blind stitch sewing machines comprising a body and a major toe portion with a minor toe portion rigidly mounted upon the presser 55 foot which is adjustable transversely rela-

tively to the needle path and is provided with a convexedly curved face converging toward the needle path operable to direct and crowd the upturned edge portion of the superimposed layer toward the path of the 60 needle. Preferably the adjustable minor toe portion is provided with an adjustable guide and also desirably with an adjustable gauge for the purposes above set forth.

Other objects and features of the invention 65 will more fully appear from the following description and the accompanying drawings and will be particularly pointed out in the claims.

A preferred embodiment of the invention 70 is disclosed herein as applied to the type of blind stitch sewing machines for sewing a superimposed layer upon a base layer of material which is illustrated and described in my prior Patents Numbers 1,469,675 and 75 1,469,676 granted October 2, 1923. The machine referred to comprises a bed plate, a standard rising therefrom provided with an arm overhanging said bed plate having a head carrying a curved oscillating and laterally vibrating needle and complementary 80 stitch forming mechanism and an upper feeding mechanism actuated by the movement of the take-up mechanism. The work is clamped between a presser foot carried by 85 a hook bracket depending from the head and a relatively movable work support which is normally held in clamping relation to the presser foot, but is separated therefrom to release and advance the work by the action 90 of the feeding mechanism. In that machine a suitable bender is reciprocably mounted in the work support and is intermittently actuated to present the upper surface of the base layer in the path of the needle during 95 its movement in one plane, while the edge portion of the superimposed layer is engaged by the needle upon its reciprocation in another plane, both of said planes of reciprocation of the needle being in the direction 100 of the line of feed and preferably substantially parallel to the line of feed.

Only a sufficient portion of the general type of machine is illustrated in the accompanying drawings to show the manner in 10 which the present invention is applied thereto.

In the drawings:

Fig. 1 is a side elevation of a portion of the stitch forming mechanism, feeding mech- 11

anism and work support of said machine, together with the presser foot which preferably carries the gauge for the edge of the superimposed layer and also embodies other features of the invention;

Fig. 2 is a front elevation of the presser foot and the guide and gauge for the edge of the superimposed layer which are adjustably mounted thereupon;

10 Fig. 3 is a plan view of the presser foot illustrated in Fig. 2;

Fig. 4 is an underside plan view of the same;

15 Fig. 5 is a sectional view through the throat portion of the presser foot viewed toward the minor toe portion showing the relative positions of the guide and gauge which are mounted upon the minor toe portion;

20 Fig. 6 is a similar view in which the gauge is omitted;

Fig. 7 is a view similar to Fig. 6 illustrating a different type of guide adapted for producing a wider seam; and,

25 Fig. 8 is a detail view of the guide illustrated in Fig. 7.

The general structure of this sewing machine may be and preferably is of the type illustrated in my prior patents aforesaid and above briefly described in which a needle bar supporting member 1 carries a needle bar 2 having a curved needle 3 which is oscillated in different planes in the direction of the line of feed and co-operates 30 with supplemental stitch forming mechanism in the form of a rotary hook 4 carried by the usual hook bracket 5. A presser foot 6 is rigidly secured to the hook bracket 5 and co-operates with a work support 7 which is carried by a standard 8 telescopically mounted in a sleeve 9 extending upwardly from the bed plate of the machine, the work support being normally held in clamping relation to the presser 40 foot by a helical spring 10 mounted within said standard. A bender 11 mounted and operating in the manner disclosed in the aforesaid patents serves to present the base layer intermittently into the path of the 45 needle.

50 The feeding mechanism comprises a horseshoe-shaped feed bar 12 which carries suitable feed dogs 13 mounted in ways in the presser foot. The feed bar and dogs are given their reciprocating feeding movement through a lever 15 which is pivotally connected at its lower end to the feed bar 12 and is actuated from the take-up, and the feed bar and dogs are given a vertical movement through an arm 16 rigidly secured to the rear end of the feed bar 12 and operated from the needle actuating mechanism, all of which mechanisms are fully disclosed in the patents aforesaid.

55 In the operation of the machine the work

is normally clamped by the work support against the presser foot. After a stitch has been formed in the base or superimposed layer the feed bar is oscillated downwardly to cause the feed dogs to depress the work support out of clamping relation to the presser foot. The feed dog is then given a longitudinal rearward movement which advances the work a distance of one stitch. The feed bar is then oscillated upwardly permitting the spring 10 to force the work support again into clamping relation to the presser foot and the dog is then advanced into position to again grasp and feed the work for another stitch.

In machines of this type guiding means are provided for presenting the edge of the superimposed layer into the path of the needle during the oscillation of the needle in one path, while the lower bender 11 is actuated to present the base layer into the path of the needle during the oscillation of the needle in the other path.

The present invention relates to means for guiding the edge of the superimposed layer into one of the paths of the oscillating vibrating needle and in its broad aspect comprises a resilient gauge, preferably of a form to embrace the upturned edge portion of the superimposed layer, and located in such proximity to the needle path that it is yieldable to the passage of the needle and the material of the superimposed layer which is caught by the needle during its penetrating stroke. Such gauge may be supported in any suitable manner, but preferably is mounted upon the minor toe of the presser foot and is adjustable transversely relatively to the needle path. The guide may be so adjusted that when a centre-pointed needle is employed the point of the needle will pass through the gauge, but the resilient gauge will yield to the passage of the body of the needle and the material of the superimposed layer which is caught by the needle and interposed between it and the resilient guide.

By reason of this construction very accurate and uniform penetration of the needle into the superimposed layer is attained and also means provided for accurately and uniformly stitching very fine sheer material when used as a superimposed layer upon the base layer. The minor toe of the presser foot desirably is also adjustably mounted rigidly upon the presser foot in order that it may be properly positioned to adapt with the greatest advantage upon materials of different thicknesses and of different character.

The adjustable presser foot desirably also provided with an adjustable and detachable guide for directing the superimposed layer toward the stitching point, the detachability of the guide permitting sub-

stitution of such guide as may be suitable for the work which is operated upon.

In the preferred embodiment of the invention illustrated in the accompanying drawings the presser foot 6 is provided with a pair of ears 17 and 18 which are secured respectively by suitable screws 19 and 20 to the hook bracket 5, the heel of the presser foot extending beneath the hook bracket as illustrated in Fig. 1. The presser foot comprises a forwardly extending toe 21 which projects from the outside of the presser foot and the under side of the toe 21 is provided with a channel 22 (see Fig. 4) forming a guideway for one feed dog. A shoe 23, extending rearwardly from the presser foot, engages the outer side of the other feed dog and acts in conjunction with the under face 24 of the heel of the presser foot and with 20 the wall of the guideway 22 to strip the goods from the feed dog when they are raised before being advanced to work engaging position.

The usual needle plate 25, which is secured to or formed integral with the under side of the presser foot, extends laterally across the line of stitching and has a curved upper surface 26 extending to the needle throat 27 and corresponding to the arc of reciprocation of the needle. The heel portion of the presser foot has a curved surface 28 also corresponding substantially to the curvature of the needle which serves to support the needle after its passage through the work and thereby prevent its deflection. The inner edge of the needle plate 25 is provided with an upwardly extending flange 29 which serves as a guide for the side of the needle in the stroke in which it penetrates the superimposed layer as is usual in blind stitch sewing machines of this type. A member 30 is secured to the upper face of the toe of the presser foot and is provided with an upwardly extending arcuate guiding flange 31 which merges into the plane of the inner edge of the guide 29 and forms an abutment against which the operator may guide the edge of the superimposed layer and cause the same to be turned upwardly as it approaches the stitching point.

The edge of the superimposed layer which is thus turned up is engaged by the guide and by the guiding and gauging means comprising the embodiment of the present invention which direct the edge of said superimposed layer into the path of the needle as heretofore described.

In the preferred embodiment of the invention disclosed herein the guide and gauge are mounted upon the minor toe of the presser foot. In the present embodiment of the invention the minor toe of the presser foot is adjustably mounted upon a toe-supporting member which is secured to one of the ears of the presser foot. As

illustrated the toe-supporting member is in the form of a substantially rectangular block 32 which is secured to the ear of the presser foot and to the hook bracket by the screw 19. It has a laterally projecting arm 33 provided with a rearwardly offset end portion having a slot 34 which is engaged by a dog 35 pivotally secured by a screw 36 to the top of the body of the presser foot. This dog is so positioned as to lock the presser foot supporting member in such position that the work engaging face of the presser foot will be properly located with respect to the surface of the superimposed layer.

The minor toe of the presser foot is in the form of a shoe 37 having an upwardly curved front end 38 and a convexedly curved rearwardly extending surface 39 converging toward the line of stitching. The shoe has a laterally extending arm 40 provided with slots 41 which receive screws 42 which are seated in the presser foot supporting member or block 32. By reason of this connection the minor toe of the presser foot may be adjusted toward and from the line of stitching. The curved converging under face of the presser foot engages the upper surface of the edge portion of the superimposed layer and acts to crowd the upturned edge of the superimposed layer toward the stitching point.

A guide 43, for the edge of the superimposed layer, is provided, this guide preferably being in the form of a plate having a downwardly curved end portion 44 which embraces the edge portion of the superimposed layer with the flat portion of the guide resting upon the top of the edge of the layer thereby limiting the height to which the edge is turned upwardly. The curved end portion 44 of the guide serves to guide the edge of the superimposed layer toward the path of the needle.

The guide plate 43 is provided with a slot to receive a clamping screw 45 by means of which it is adjustably secured to the minor toe of the presser foot and is adapted to be adjusted relatively to said minor toe and to the needle path. The other end 46 of the guide 43 desirably is of a reduced width and extends into a slot in the laterally extending arm 40 of the minor toe.

This guide can be detached by removing the screw 45 and other guides substituted therefor according to the character of the material of which the superimposed layer is formed, or for producing wider stitches in the superimposed layer, that is to say stitches which are located at a greater distance from the edge of the superimposed layer. An illustrative substitute guide 47, adapted to produce a wider seam of this character, is illustrated in Fig. 8.

This guide obviously may alone be used to

direct the edge of the superimposed layer into the path of the needle and the adjustability of this guide together with the adjustability of the minor toe of the presser foot, which serves to crowd the edge of the superimposed layer toward the needle path, provides means for properly guiding various different thicknesses and characters of the material of the superimposed layer into the path of the needle.

While the presser feet of blind stitch sewing machines have heretofore been provided with guides somewhat similarly located, so far as I am aware no presser foot has heretofore been provided with a minor toe portion which is adjustable toward and from the line of stitching, or with an adjustable and detachable guide mounted upon an adjustable minor toe portion of the presser foot. The present construction enables a greater variety of superimposed layer material to be properly presented to the stitch forming mechanism than in other constructions heretofore produced.

In addition to the novel guiding means for the superimposed layer the present invention comprehends the additional means for insuring uniformity and accuracy of stitching in the superimposed layer above generally described.

In the particular embodiment of the invention herein this mechanism is in the form of a gauge comprising a resilient plate 48 of general L-shape form having a shank 49 provided with a slot 50 which receives a clamping screw 51 which is seated in the under surface of the presser foot supporting block 32 (see Fig. 4). The gauge is provided with a central upwardly curved portion 52 which increases its resilience and a downwardly curved end portion 53 positioned to embrace the edge of the superimposed layer at the stitching point. The end portion of the gauge 49 desirably lies in such close proximity to the needle path that the point of a centrally pointed needle may pass through the gauge adjacent its downwardly curved end, but the resilient gauge will be raised by the body portion of the needle and the material which is caught by the needle during its penetrating stroke.

By reason of this construction exceeding accuracy and uniformity of penetration of the needle in the superimposed layer and the length of the stitch therein is attained and skipping of stitches by the needle is obviously avoided.

The gauge may be adjusted for different thicknesses or character of material by loosening the screw 51 and sliding the shank of the gauge toward or from the path of the axis of the needle as may be required.

In order to insure accuracy of the penetration of the needle in the base layer an abut-

ment is provided for limiting the upward movement of the bender 11 in such a manner that a predetermined depth of stitching will be made in the base layer irrespective of the goods of said base layer. As illustrated herein a stop or abutment is provided which is of L-shaped form, the vertical arm 54 having a flat under surface to engage the base layer immediately above the axis of the bender, while the laterally extending arm 55 is provided with an enlarged end 56 which is pivotally mounted upon the screw 20 by which the ear 18 of the presser foot is secured to the hook bracket 5. An adjusting screw 57 having a slotted top passes through the arm 55 of the L-shaped stop member and is seated in the major toe portion 21 of the presser foot. A suitable spring acts normally to raise the abutment or stop 54. As illustrated herein the spring is of L-shaped form comprising a horizontal portion 58 having a down-turned end which rests upon the top of the major toe portion of the presser foot and a vertical portion 59 which is secured by a screw 60 to the horizontal arm 55 of the abutment member. The vertical portion 59 of the spring is provided with laterally extending wings 61 which engage the knurled periphery of the adjusting screw 57. The spring 58, therefore, holds the arm 55 of the abutment pressed upwardly against the under face of the set screw and by adjusting the set screw the position of the lower end of the stop or abutment can be accurately positioned to limit the upward movement of the lower bender.

It will be understood that the embodiment of the invention disclosed herein is illustrative in character and is not restrictive and that various modifications in form, construction and arrangement of parts may be made within the scope of the invention.

It will also be understood that the invention may be applied to other types of presser foot or embodied in other blind stitch sewing machine constructions within the spirit and scope of the following claims.

Having thus described the invention, what is claimed as new, and desired to be secured by Letters Patent, is:

1. A blind stitch sewing machine for sewing the edge portion of a superimposed layer upon a base layer of material comprising a needle reciprocable in the general direction of the line of feed and a resilient gauge for the said edge portion of the superimposed layer located in close proximity to the needle path and yieldable to the passage of the needle and the material of the superimposed layer caught by the needle during its penetrating stroke.

2. A blind stitch sewing machine for sewing the edge portion of a superimposed layer upon a base layer of material comprising a needle reciprocable in the general direction

of the line of feed, a resilient gauge for the said edge portion of the superimposed layer located in close proximity to the needle path and yieldable to the passage of the needle 5 and the material of the superimposed layer caught by the needle during its penetrating stroke and means for adjusting said gauge transversely relatively to the needle path.

3. A blind stitch sewing machine for sewing the edge portion of a superimposed layer upon a base layer of material comprising a needle reciprocable in the general direction of the line of feed and a resilient gauge having means to embrace the edge portion of the superimposed layer at the stitching point 15 and yieldable to the passage of the needle and the material of the superimposed layer caught by the needle during its penetrating stroke.

20 4. A blind stitch sewing machine for sewing the edge portion of a superimposed layer upon a base layer of material comprising a needle reciprocable in the general direction of the line of feed, a resilient gauge having means to embrace the edge portion of the superimposed layer at the stitching point 25 and yieldable to the passage of the needle and the material of the superimposed layer caught by the needle during its penetrating 30 stroke and means for adjusting said gauge transversely relatively to the needle path.

5. A blind stitch sewing machine for sewing the edge portion of a superimposed layer upon a base layer of material comprising a needle reciprocable in the general direction of the line of feed, a presser foot having a major toe portion to engage the base layer and a minor toe portion rigidly secured to said presser foot and provided with a convexedly curved surface converging rearwardly toward the needle path to engage the upturned edge of the superimposed layer and a resilient gauge mounted upon said minor toe portion having means to embrace 40 the edge of the superimposed layer at the stitching point.

6. A blind stitch sewing machine for sewing the edge portion of a superimposed layer upon a base layer of material comprising a needle reciprocable in the general direction of the line of feed, a presser foot having a major toe portion to engage the base layer and a minor toe portion rigidly secured to said presser foot and provided with a convexedly curved surface converging rearwardly toward the needle path to engage the upturned edge of the superimposed layer, a resilient gauge mounted upon said minor toe portion having means to embrace 55 the edge of the superimposed layer at the stitching point and means for adjusting the minor toe transversely relatively to the needle path.

7. A blind stitch sewing machine for sewing the edge portion of a superimposed layer

upon a base layer of material comprising a needle reciprocable in the general direction of the line of feed, a presser foot having a major toe portion to engage the base layer and a minor toe portion rigidly secured to 70 said presser foot and provided with a convexedly curved surface converging rearwardly toward the needle path to engage the upturned edge of the superimposed layer, a resilient gauge mounted upon said minor toe portion having means to embrace 75 the edge of the superimposed layer at the stitching point, means for adjusting the minor toe transversely relatively to the needle path and means for adjusting said 80 resilient gauge upon said minor toe relatively to the needle path.

8. A blind stitch sewing machine for sewing the edge portion of a superimposed layer upon a base layer of material comprising a 85 needle reciprocable in the general direction of the line of feed, a presser foot having a major toe to engage the base layer and a minor toe rigidly secured to said presser foot and provided with a convexedly curved surface converging rearwardly 90 toward the needle path to engage the upturned edge of the superimposed layer, means adjustably securing said minor toe to said presser foot to permit said minor toe to be adjusted transversely relatively to the needle path, an edge guide for the superimposed layer and means for adjustably securing the same to said minor toe.

9. A blind stitch sewing machine for sewing the edge portion of a superimposed layer upon a base layer of material comprising a needle reciprocable in the general direction of the line of feed, a presser foot having a major toe to engage the base layer and a minor toe rigidly secured to said presser foot and provided with a convexedly curved surface converging rearwardly toward the needle path to engage the upturned edge of the superimposed layer, means adjustably 10 securing said minor toe to said presser foot to permit said minor toe to be adjusted transversely relatively to the needle path, an edge guide for the superimposed layer comprising a resilient plate adjustably secured to said minor toe and having a curved 11 end to embrace the upturned edge of the superimposed layer.

10. A blind stitch sewing machine for sewing the edge portion of a superimposed layer upon a base layer of material comprising a needle reciprocable in the general direction of the line of feed, a presser foot having a major toe to engage the base layer and a minor toe rigidly secured to said presser foot and provided with a convexedly curved surface converging rearwardly toward the needle path to engage the upturned edge of the superimposed layer, means adjustably 12 securing said minor toe to said presser foot 13

- to permit said minor toe to be adjusted transversely relatively to the needle path, an edge guide for the superimposed layer comprising a resilient plate adjustably secured to said minor toe and having a curved end to embrace the upturned edge of the superimposed layer and a gauge adjustably mounted upon said minor toe portion having means to embrace the edge of the superimposed layer at the stitching point and yieldable to the passage of the needle and the material of the superimposed layer caught by the needle during its penetrating stroke.
11. A blind stitch sewing machine for sewing the edge portion of a superimposed layer upon a base layer of material comprising a curved needle reciprocable in the general direction of the line of feed, a hook bracket and complemental stitch forming mechanism carried thereby, a presser foot secured to said hook bracket and provided with a major toe portion, a minor toe portion supporting member pivotally secured to said presser foot, co-operating interengaging members upon said minor toe supporting member and said presser foot operable when engaged properly to position said minor toe relatively to the plane of the work engaging surface of the presser foot and means for adjusting said minor toe upon its supporting member transversely relatively to the needle path.
12. A blind stitch sewing machine for sewing the edge portion of a superimposed layer upon a base layer of material comprising a curved needle reciprocable in the general direction of the line of feed, a hook bracket and complemental stitch forming mechanism carried thereby, a presser foot secured to said hook bracket and provided with a major toe portion, a minor toe portion supporting member pivotally secured to said presser foot, co-operating interengaging members upon said minor toe supporting member and said presser foot operable when engaged properly to position said minor toe relatively to the plane of the work engaging surface of the presser foot, means for adjusting said minor toe upon its supporting member transversely relatively to the needle path, a guide adjustably secured to said minor toe and a gauge having means for embracing the upturned edge of the superimposed layer adjustably and detachably secured to said minor toe.
13. A blind stitch sewing machine for sewing the edge portion of a superimposed layer upon a base layer of material comprising a curved needle reciprocable in the general direction of the line of feed, a hook bracket and complemental stitch forming mechanism carried thereby, a presser foot having ears secured to said hook bracket and provided with a major toe portion, a minor toe supporting member pivotally secured to one of the ears of the presser foot and having a laterally extending arm provided with a recessed end portion and a dog pivotally mounted upon said presser foot positioned to engage the notch in said arm and thereby to lock said minor toe portion in proper position relatively to the plane of the work engaging surface of said presser foot.
14. A presser foot for blind stitch sewing machines having a needle reciprocable in the general direction of the line of feed comprising a major toe portion having a guide for the needle and a needle throat, a minor toe portion and means for adjusting said minor toe portion transversely relatively to the line of stitching.
15. A presser foot for blind stitch sewing machines having a needle reciprocable in the general direction of the line of feed comprising a major toe portion having a guide for the needle and a needle throat, a minor toe portion, means for adjusting said minor toe portion transversely relatively to the line of stitching and a resilient gauge adjustably mounted upon said minor toe portion having means to embrace the upturned edge of the superimposed layer and yieldable to the passage of the needle and the material of the superimposed layer caught by the needle during the penetrating stroke.
16. A presser foot for blind stitch sewing machines having a needle reciprocable in the general direction of the line of feed comprising a major toe portion having a guide for the needle and a needle throat, a minor toe portion, means for adjusting said minor toe portion transversely relatively to the line of stitching, a resilient gauge adjustably mounted upon said minor toe portion having means to embrace the upturned edge of the superimposed layer and yieldable to the passage of the needle and the material of the superimposed layer caught by the needle during the penetrating stroke and a guide for the superimposed layer adjustably secured to said minor toe portion in advance of said gauge.
17. A presser foot for blind stitch sewing machine for sewing the edge portion of a superimposed layer upon a base layer of material having a needle reciprocable in the general direction of the line of feed comprising a resilient gauge having means to embrace the edge portion of the superimposed layer at the stitching point and yieldable to the passage of the needle and the material of the superimposed layer caught by the needle during its penetrating stroke.

In testimony whereof, I have signed my name to this specification.

HARLEY C. MOULTON.
